(57) **CLAIM**

The ornamental design for a healthcare privacy label, as shown and described.

DESCRIPTION

FIG. 1 is a perspective view of a healthcare privacy label embodying our new design, illustrating the privacy label applied to an exemplary prescription bottle;

FIG. 2 is a perspective view showing the patient identification portion of the privacy label peeled away;

FIG. 3 is a front elevational view thereof;

FIG. 4 is a top plan view thereof;

FIG. 5 is a rear elevational view thereof;

FIG. 6 is a bottom plan view thereof;

FIG. 7 is a left side elevational view thereof;

FIG. 8 is a right side elevational view thereof;

FIG. 9 is a front elevational view similar to FIG. 1, illustrating how a tab extends slightly from a backing; and,

FIG. 10 is a front elevation view showing the patient identification portion of the privacy label peeled away.

The prescription bottle shown in broken lines in FIGS. 1 and 2 forms no part of the claimed design. The brake lines in the drawings indicate no specific length.

The broken lines on the privacy label represent perforations or a score line.
